Roy M. Jenkins, Los Angeles, Calif., assignor to Lindy
Pen Company Incorporated, North Hollywood, Calif.

Filed May 14, 1970, Ser. No. 22,982

Term of patent 14 years

Int. Cl. D19—06
U.S. Cl. D74—17 C

FIG. 2.

FIG. 3.

FIG. 4.

FIG. 5.

FIG. 1 is a side view of a barrel for a writing instrument showing my new design;

FIG. 2 is an enlarged side view of a section of the barrel shown in FIG. 1;

FIG. 3 is a cross sectional view thereof taken along the lines 3—3 of FIG. 2;

FIG. 4 is an enlarged cross sectional view of another embodiment of the barrel for a writing instrument shown in FIG. 1 disclosing an alternative structure for providing the same appearance; and

FIG. 5 is an enlarged cross sectional view of a further embodiment thereof disclosing yet another structure for achieving the same overall appearance.

The dominant feature of the design resides in the internal scoring of the transparent barrel.

I claim:

The ornamental design for a barrel for a writing instrument, as shown and described.
